UNITED STATES PATENT OFFICE.

LOUIS F. CASTELLI, OF NORTH BERGEN, NEW JERSEY.

JAR-CAP REMOVER.

Application filed August 9, 1927. Serial No. 211,706.

This invention relates to gripping tools of the pliers type, and while particularly designed and adapted as a jar cap remover, it is understood that the same may be employed 5 in other capacities in which it may be used.

In view of the fact that tools of this nature are employed in connection with jar caps or analogous articles which vary in diameter, it has been found that where the 10 jaws and operating handles are rigid, grasping of the handles by one hand where the jaws are associated with caps of large diameters, is practically impossible.

It is therefore an object of the present invention to provide a gripping tool in which at least one jaw and its operating handle are relatively adjustable to compensate for the use of the tool upon objects of varying diameters.

20 The invention furthermore comprehends in a gripping tool of the character set forth, a simple and effective adjustable connection between a jaw and its operating handle.

With the above recited and other objects 25 in view, reference is had to the following description and accompanying drawings in which there is exhibited one example or embodiment of the invention, while the appended claims define the actual scope of the 30 invention.

In the drawings—

Figure 1 is a plan view of the tool with the jaws in closed condition and illustrating the adjustable operating handle adjusted for minimum sized objects to be gripped;

35 Fig. 2 is a similar view with the jaws opened and illustrating the adjustable handle adjusted to the position for gripping objects of a maximum size;

40 Fig. 3 is a fragmentary plan view illustrating the adjustable handle in an intermediate disengaged position with respect to its jaw;

45 Fig. 4 is an enlarged fragmentary sectional view taken approximately on the line 4—4 of Fig. 2.

Referring to the drawings by characters of reference, 10 and 11 designate a pair of gripping jaws, which may be of any desired 50 configuration, which in the present instance are of arcuate shape and provided on the inner concave faces with gripping teeth 12 so that the tool may be employed for gripping and turning circular articles such as 55 jar caps. The jaw 10 is provided with a substantially circular base or hub 13, which

base has extending from a substantially diametrically opposite point from which the jaw extends, a handle shank 14 carrying a handle 15. The handle shank 14 may be 60 either integral or otherwise rigidly connected with the jaw base 13. The other jaw 11 is provided with a similar circular base or hub 16 which overlies the base or hub 13 and through which bases or hubs a 65 pivot 17 axially extends to pivotally connect the jaws for relative opening and closing movement.

An operating handle 18 for the jaw 11 includes a shank 19, which is provided with a 70 slotted end 20 through which the pivot bolt 17 also extends. The peripheral base or hub 16 of the jaw 11 at a point substantially diametrically opposite the jaw 11, is provided with a plurality of circumferentially 75 spaced notches or recesses 21, while the handle shank 19 is provided with a detent 22 adapted for selective engagement in the recesses or notches 21 to dispose the operating handle 18 at relatively different angularly 80 adjusted positions with respect to the jaw 11. In order to provide means for sliding the handle longitudinally to normally engage and retain the detent 22 within the notches or recesses 21, a coiled expansion 85 spring 23 is positioned within the slot 20, the opposite ends bearing respectively against the pivot bolt 17 and the outermost end of the slot 20. In order to prevent derangement or positive accidental displacement of the spring from the slot, the outer 90 end convolution of the spring is provided with an axial outwardly projecting terminal 24 which extends into an opening 25 in the extremity of the handle shank 19. In 95 order to limit outward sliding movement of the handle to a point where the detent clears the periphery of the base or hub 16 of the jaw 11, a pin 26 is arranged within the convolutions of the spring 23 so that its opposite ends are engaged respectively by the outermost end of the slot and the pivot bolt 17.

In use, when a jar cap or object of a minimum size is to be gripped and turned by the tool, the detent 22 is engaged in the recess or notch 21 which will dispose the handle in such a position that when the tool jaws are closed, the handles will be disposed in substantially parallel relation. If a jar cap or object of larger diameter is to be gripped and turned, it is obvious that the detent 22

may be engaged in one of the remaining notches suitable to the particular diameter of the object to be gripped. This disposes the jaws 10 and 11 in an open position when the handles are in substantially parallel relation so that an unduly wide separation of the handles to obtain a grip on the object, is unnecessary. It therefore follows that the operator may employ one hand for setting up the desired grip of the jaws upon the object to be gripped and turned. In adjusting the handle 18, it is only necessary to pull outwardly against the action of the spring 23 until the detent 22 is completely disengaged from the notch or recess 21 with which it is engaged and then to turn the handle relative to the base or hub 16 of the jaw 11, until the detent registers with the desired notch or recess 21. The spring will operate to re-engage the detent in the notch selected and retain the same in said notch until a further adjustment is desired.

It is, of course, to be understood, within the scope of the invention, that both jaws may have their handles adjustably connected therewith if so desired so as to further increase the variation of the adjustment of the tool.

What is claimed is:

- 30 1. A gripping tool, comprising a pair of jaws, each having a substantially circular base or hub, a pivot extending axially therethrough and pivotally connecting the same, an operating handle for one jaw, rigidly connected with the base thereof, an operating handle for the other jaw pivotally carried by said pivot, means for adjustably coupling said latter handle with the base of its jaw, whereby to regulate relative opening of the jaws without affecting the normal opening of the handles, said means consisting of a slotted end of said handle engaged over the pivot, a detent on said handle and circumferentially spaced peripheral notches

in the jaw base, means for normally moving the handle with respect to the jaw base to engage and retain the detent in the notches, said latter means consisting of a coiled expansion spring arranged within the slotted end of the handle and interposed between the outer end of the slot and the pivot, and means for limiting outward sliding movement of the handle with respect to the jaw base, consisting of a stop pin loosely disposed within the convolutions of said spring and of a length to engage with the outer end of the slot and the pivot pin when the detent is disengaged from the notches.

2. A gripping tool comprising a pair of gripping jaws, each having a base, a pivot extending axially therethrough, an operating handle rigidly connected with the base of one jaw, an operating handle for the other jaw carried by said pivot and means for adjustably coupling said latter handle with the base of its jaw, whereby to regulate the relative opening of the jaws without affecting the normal opening of the handles, said means comprising a slotted end of said handle engaged over the pivot, interengaging devices on said handle and its jaw base, a coiled expansion spring arranged within the slotted end of the handle and interposed between the outer end of the slotted portion and the pivot, and means for limiting the outward sliding movement of the handle with respect to its jaw base consisting of a stop pin loosely disposed within the convolutions of said spring and of a length to engage with the outer end of the slot and the pivot pin when the interengaging devices are disengaged for permitting of the adjustable coupling of the handle to the jaw.

Signed at Union City in the county of Hudson and State of New Jersey this sixth day of August A. D. 1927.

LOUIS F. CASTELLI.
